UNITED STATES PATENT OFFICE.

ELMER E. WILKINSON AND SAUL ARONSON, OF BROOKLYN, NEW YORK, ASSIGNEES,
BY MESNE ASSIGNMENTS, TO THE SILENT MOTOR CORPORATION, OF BROOKLYN,
NEW YORK, A CORPORATION OF NEW YORK.

SPEED-REGULATING MECHANISM FOR SPRING MOTORS.

1,402,985.

Specification of Letters Patent. Patented Jan. 10, 1922.

Application filed September 4, 1920. Serial No. 408,152.

To all whom it may concern:

Be it known that we, ELMER E. WILKINSON, a citizen of the United States, and a resident of the city of New York, borough of Brooklyn, county of Kings, and State of New York, and SAUL ARONSON, a citizen of the United States, and a resident of the city of New York, borough of Brooklyn, county of Kings, and State of New York, 10 have invented certain new and useful Improvements in Speed-Regulating Mechanism for Spring Motors, of which the following is a full, clear, and exact specification.

Our invention is an improvement in 15 mechanism for regulating the speed of operation of spring motors and finds special application in phonograph motors.

The objects and advantages of our invention will become evident from a detailed 20 description of the illustrative embodiment shown in the accompanying drawings, in which—

Fig. 1 is a plan view of a speed-regulating mechanism constructed in accordance with 25 our invention, a portion of the top plate being broken away to expose the parts beneath;

Fig. 2 is a view in elevation of the mechanism shown in Fig. 1, looking in the direction of the arrow *a*;

Fig. 3 is a sectional view approximately 30 on line 3—3 of Fig. 1; and

Fig. 4 is a detached view in perspective of our improved brake lever.

As our invention is applicable to spring 35 motors of various types and constructions, we have shown only a portion of a conventional form of motor. The framework or casting *A*, which supports the parts of the 40 motor, is here shown secured to the under side of the supporting member or top board 1 of a phonograph cabinet 2. The vertical shaft 3, which supports the turntable 4, is driven by the motor spring or springs 45 in the usual manner. As the driving connections between the springs and the shaft 3 are well understood by those acquainted with these devices, we have not deemed it necessary to show them, except that we have 50 incidentally shown the worm-pinion 5 at the lower end of the shaft 3 in mesh with the worm gear 5' carried at the lower end of a shaft 7, which is driven from one of the

spring barrels contained in motors of this kind. The turntable shaft 3 is provided with 55 a worm-gear 8, adapted to mesh with the worm 9 on the governor shaft 10, on which are mounted the centrifugal weights 11 and the brake disk 12. This is the usual construction of speed governors of this type, and 60 as their operation is a matter of common knowledge among mechanics, nothing further need be said on this point.

The framework or casting *A* of the motor carries the pin or stud 13 on which is pivoted 65 a bellcrank consisting of an arm or lever 14 having a depending extension 15. The form of this extension is best shown in Fig. 4, where it will be seen that the extension is roughly circular, terminating in the upwardly projecting portion 16. The extension 15 is provided with a pair of aligned bearings in the form of small holes 17, in which is pivoted a yoke 18. This yoke is substantially annular in form except that it has a 70 break or opening 19, as shown in Fig. 4. The yoke 18 is provided with a pair of small projections arranged to fit into the bearing holes 17 of the extension 15, whereby the yoke swings freely on the extension. The 75 extension 15 is sufficiently resilient to permit the yoke 18 to be easily snapped into place and as readily removed when required. The yoke 18 is provided with a pair of friction pads 20, arranged to engage the side of the 80 disk 12 which, as is usual in governor constructions of this kind, is slidable on and rotatable with governor shaft 10.

The operation of the brake lever will be 85 clear from the foregoing, and may be briefly stated as follows: When the lever 14 is moved upwardly, the extension 15 and the yoke 18 move toward the right (as viewed in Fig. 3), and consequently the disk 12 is allowed to move toward the right under the 90 centrifugal action of the weights 11, the result being an increase of speed of the turntable shaft 3. When the lever 14 is depressed, the yoke 18 is moved toward the left (as viewed in Fig. 3) and carries with 95 it the disk 12. This shifting of the disk 12 causes a decrease in the speed of the shaft 3 in a manner well understood. The swinging yoke 18 permits the friction pads 20 to 100 adjust themselves automatically to any unevenness in the side of the disk 12, or to any 105

wobbling movement of the disk. Also, since the extension 15 is rigidly secured to the lever 14 and therefore moves in the arc of a circle, the pivotal mounting of the yoke 18 is necessary to permit the pads 20 always to maintain a parallel position with respect to the disk 12, so that both pads bear evenly against the disk. This automatic adjustment of the pads eliminates the undesirable noises which have been found to occur in speed-controlling devices heretofore constructed. One of the indispensable features of a good spring motor is noiselessness of operation, and anything which tends to produce even a slight noise is objectionable; hence, the advantage of the automatically adjustable yoke 18.

The purpose of the opening or break 19 in the yoke 18 is to permit the brake lever to be attached in position and removed therefrom without disturbing the governor shaft 10, which passes substantially through the center of the yoke 18, as indicated in dotted lines in Fig. 4.

Having thus described the construction and operation of the brake lever, we will now describe the connections for adjusting this lever by merely turning a finger piece at the top of the motor board, whereby the speed of the spring motor is quickly and accurately regulated. On one side of the casting A is supported a plate 21 which, in this instance, consists of two parallel offset portions so as to be accommodated on the particular form of casting shown. The precise configuration of the plate 21 is immaterial. The plate 21 is slidably supported on the casting by means of slots 22 which engage screws or pins 23 secured to the casting. Near its forward end the plate 21 is provided with a slanting slot 24, as best shown in Fig. 2. The free end 25 of the lever 14 extends into the slot 24. Suitable spring means, such as coil-spring 26 on the stud 13, normally tends to throw the lever 14 upwardly, so that the tongue or extension 25 of this lever is always held against the upper edge of the slot 24. It will be clear from Fig. 2, that when the plate 21 is shifted toward the left, the lever 14 rocks upwardly under the action of the spring 26, the extent of this upward movement being governed by the degree of inclination of the slot 24, or rather of the upper edge thereof. If we assume the plate 21 to be at its extreme left position, the shifting of the plate toward the right will gradually depress the lever 14. In other words, the shifting of the plate 21 toward the right (as viewed in Fig. 2) decreases the speed of the turntable shaft 3, while movement of the plate in the opposite direction increases the speed of the shaft 3.

A link 27 is pivoted at its inner end to a 65 stud 28 which passes through the lateral ex-

tension 29 of the slidable plate 21. The other end of the link 27 is provided with an elongated slot 30 which has a row of teeth 31 on one side or edge thereof, as shown in Fig. 1. A rotatable pin 32, held in a sleeve 32', extends through the top board 1, and is at its lower end provided with teeth 33 which mesh with the teeth 31 of the link 27. The upper end of the pin 32 terminates in a knurled head 34, by which it is readily 75 grasped by the fingers for moving in one direction or the other. A pointer 35 is connected to the pin and moves therewith over a suitably graduated scale 36 fastened to the board 1.

Referring to Fig. 1, it will be seen that when the pin 32 is turned counter-clockwise, the link 27 and plate 21 are shifted toward the left, and the speed of the motor is increased. In the position of the parts shown in Figs. 1 and 2, the speed of the motor is at its lowest. The pointer 35 indicates this by being at the "slow" end of the scale 36. If the pin 32 is turned so as to bring the pointer 35 to the opposite or "fast" end of the scale, 90 the motor will be running at its highest speed limit. In order to secure any intermediate speed of the turntable shaft 3, the pin is turned one way or the other to bring the pointer 35 to the correspondingly marked 95 division on the scale.

It will be seen from Fig. 2, that the teeth 33 on the pin 32 extend axially for a considerable distance. This permits a vertical adjustment of the pin with respect to the link 27 without interfering with the operative connection between the teeth 33 and 31. This adjustability of the pin 32 is a desirable and advantageous feature, because it is a fact that the top boards, or motor boards 105 as they are usually called, in phonographs vary in thickness even in the same style or design of machine. One difficulty with speed-controlling mechanisms of prior construction has been that the finger pin which carries the pointer required a certain adjustment with respect to the connections underneath the motor board, so that when there was a variation in the thickness of the motor boards in the different machines, the 110 predetermined vertical adjustment of the indicator pin would not apply to the different machines. As a result it was necessary to adjust the pin for each machine separately, thereby requiring extra time and expense in the assembling of the parts. These difficulties and objections are entirely eliminated by the simple connections which we have provided between the link 27 and the pin 32, for the latter may be vertically adjusted within all practical limits without disengaging the teeth 33 from the teeth 31. Furthermore, no special manipulation is required to connect the pin 32 with the link 115 27. All that is necessary is simply to push 120 the pin 32 into the sleeve 32' until the teeth 33 mesh with the teeth 31. The pin 32 is 125 held in the sleeve 32' by a set screw which is not shown in Fig. 1. The sleeve 32' is fastened to the top board 1 by a screw 37 which passes through the top board 130

- that the untoothed portion of the pin forms a smooth bearing contact with the untoothed side of the slot in said link when the pin is turned, the teeth on said pin extending 5 axially a sufficient distance to permit vertical adjustment of said pin without breaking operative connection with said link, and speed-controlling mechanism controlled by said link.
- 10 6. In speed-controlling mechanism for spring motors, a framework or casting in which the motor is mounted, a plate slidably mounted on said framework so as to have a horizontal movement in either direction, a slanting or cam-shaped slot provided in said plate, a lever mounted on said framework so as to move up and down, the free end of said lever engaging in said slot, whereby a horizontal movement of said 15 plate produces a corresponding vertical movement of said lever, speed-controlling mechanism controlled by said lever, a vertical pin adapted to be turned by hand in either direction, and a member operatively connected at one end with said pin and at the other end with said plate for translating the rotary motion of the pin in either direction into a corresponding sliding movement of the plate.
- 20 7. In speed-controlling mechanism for spring motors, a framework or casting in which the motor is mounted, a plate slidably mounted on said framework so as to have a horizontal movement in either direction, a slanting or cam-shaped slot provided in said plate, a lever mounted on said framework so as to move up and down, the free end of said lever engaging in said slot, whereby a horizontal movement of said 25 plate produces a corresponding vertical movement of said lever, speed-controlling mechanism controlled by said lever, a vertical pin adapted to be turned by hand in either direction, and having teeth at its 30 lower end, and a member connected at one end to said plate and at the other end having teeth in mesh with the teeth on said pin, whereby the turning of the pin in either direction produces a corresponding sliding 35 movement of the plate.
8. In speed-controlling mechanism for spring motors, a governor shaft, a brake disk on said shaft, a pivoted lever provided with a curved extension, a substantially ring-shaped yoke pivoted in said extension and having friction pads arranged to engage the face of said disk, said shaft passing through said yoke, said yoke having a break or opening in its annular part to permit the ready insertion and removal 40 of the yoke and lever into and from operative position without disturbing the governor shaft, and means for controlling said lever.
9. In speed-controlling mechanism for spring motors, a governor shaft, a brake disk on said shaft, a pivoted bell-crank lever, one arm of said lever consisting of a laterally curved extension partially passing around said shaft, said extension being resilient and provided with a pair of bearings, a substantially ring-shaped yoke pivoted in said bearings and having friction pads arranged to engage the face of said disk, said shaft passing through said yoke, said yoke 45 having a break or opening in its annular part to permit the ready insertion and removal of the yoke and lever into and from operative position without disturbing the governor shaft, and means engaging the other arm of said lever to actuate the same and move the yoke into the desired position relative to said disk.
10. In speed-controlling mechanism for spring motors, a supporting member beneath which the motor is secured, a manually operable vertically-extending toothed pin rotatably mounted in said supporting member, a link carried by said motor framework and provided with a slot having teeth 50 engaged by the teeth of said pin whereby rotation of said vertically-extending pin produces a movement of said link and speed controlling mechanism controlled by movement of said link.

Signed at the city of New York, in the county of New York, State of New York, this 3rd day of September, 1920.

ELMER E. WILKINSON.
SAUL ARONSON.

the pin 32 downwardly and the teeth 33 will easily slide into engagement with the teeth 31.

It will also be observed that the teeth 33 of the pin 32 do not extend entirely around the pin, but there is an untoothed portion 37, as shown in Figs. 1 and 2. This untoothed portion 37 forms a noiseless contact or bearing for the untoothed edge 38 of the slot 30, whereby the operation of the pin 32 and link 27 is rendered easy and noiseless.

Although we have set forth a specific form of mechanism, it is obvious that changes and modifications may be made without departing from the scope of the invention as defined in the appended claims.

What we claim as our invention is:

1. In speed-controlling mechanism for spring motors, a framework or casting in which the motor is mounted, a vertical turntable shaft adapted to be driven by the motor spring, a governor for controlling the speed of said shaft, said governor including a brake disk slidably mounted on the governor shaft, a lever pivoted on said framework so as to move up and down, a yoke carried by said lever and having friction pads arranged to engage the face 30 of said disk, a plate slidably mounted on said framework so as to have a horizontal movement, said plate being provided with a slanting or cam-shaped slot, the free end of said lever projecting through said slot, whereby the horizontal shifting of said plate effects a vertical rocking of said lever and a corresponding movement of the brake yoke, a horizontally shiftable link connected at one end to said plate and having an elongated slot at the other end, one side of said slot being provided with teeth, a vertical rotatable pin having teeth on its lower portion adapted to engage the teeth of said slotted link, whereby a rotary movement of said pin in either direction causes a corresponding sliding movement of said link and said plate, the teeth on said pin extending axially a sufficient distance to permit vertical adjustment of said pin without 50 breaking operative connection with said link, and means for manually turning said pin in either direction.

2. In speed-controlling mechanism for spring motors, a top board beneath which the motor framework is secured, a vertical pin rotatably mounted on said board and extending therethrough, means for turning said pin by hand in either direction, teeth provided in the lower portion of said pin, a horizontally movable link carried by the framework, one end of said link having an elongated slot provided on one side with teeth, the lower portion of said pin projecting through said slot, so that the teeth of said pin mesh with the teeth of said

link, whereby a rotary movement of the pin in either direction produces a corresponding slidable movement of the link, and speed-controlling mechanism controlled by said link.

3. In speed-controlling mechanism for spring motors, a top board beneath which the motor framework is secured, a vertical pin rotatably mounted on said board and extending therethrough, means for turning 75 said pin by hand in either direction, teeth provided on the lower portion of said pin, a horizontally movable link carried by the framework, one end of said link having an elongated slot provided on one side with 80 teeth, the lower portion of said pin projecting through said slot, so that the teeth of said pin mesh with the teeth of said link, whereby a rotary movement of the pin in either direction produces a corresponding slidable movement of the link, the teeth on 85 said pin extending only partway around, so that the untoothed portion of the pin forms a smooth bearing contact with the untoothed side of the slot in said link when the pin is turned, 90 and speed-controlling mechanism controlled by said link.

4. In speed-controlling mechanism for spring motors, a top board beneath which the motor framework is secured, a vertical 95 pin rotatably mounted on said board and extending therethrough, means for turning said pin by hand in either direction, teeth provided on the lower portion of said pin, a horizontally movable link carried by the 100 framework, one end of said link having an elongated slot provided on one side with teeth, the lower portion of said pin projecting through said slot, so that the teeth of said pin mesh with the teeth of said link, whereby a rotary movement of the pin in either direction produces a corresponding slidable movement of the link, the teeth on 105 said pin extending axially a sufficient distance to permit vertical adjustment of said pin without 110 breaking operative connection with said link, and speed-controlling mechanism controlled by said link.

5. In speed-controlling mechanism for spring motors, a top board beneath which the motor framework is secured, a vertical 115 pin rotatably mounted on said board and extending therethrough, means for turning said pin by hand in either direction, teeth provided in the lower portion of said pin, a horizontally movable link carried by the 120 framework, one end of said link having an elongated slot provided on one side with teeth, the lower portion of said pin projecting through said slot, so that the teeth of 125 said pin mesh with the teeth of said link, whereby a rotary movement of the pin in either direction produces a corresponding slidable movement of the link, the teeth on said pin extending only partway around, so 130
